UNITED STATES PATENT OFFICE.

THOMAS P. GREGER, OF PHILADELPHIA, PENNSYLVANIA.

DESIGN FOR A MANHOLE-COVER.

SPECIFICATION forming part of Design No. 27,673, dated September 21, 1897.

Application filed August 3, 1897. Serial No. 646,982. Term of patent 14 years.

To all whom it may concern:

Be it known that I, THOMAS P. GREGER, a citizen of the United States, residing at the city of Philadelphia, in the county of Philadelphia and State of Pennsylvania, have invented and produced a new and original Design for Manhole-Covers, of which the following is a specification, reference being had to the accompanying drawings, forming a part thereof.

Figure 1 is a top or plan view of a manhole-cover, showing my design; and Fig. 2 is a central vertical sectional view of the same.

The leading feature of my design consists in the raised rib-like projections, which, when viewed in plan, as in Fig. 1, are arranged entirely within a circular or substantially circular outline in two series crossing each other at right angles to form the appearance of a checker-board, and which when viewed in section, as in Fig. 2, appear to project upward from a concaved base.

Referring to the drawings, A is the base of the manhole-cover, which in outline is substantially circular and in vertical section is

dish-shaped or concave. From this concave base A extend the rib-like projections B D in two series, both arranged within the circular outline, and one series B arranged at right angles to the other series D, thus dividing the circular base into a series of squares E in the manner of a checker-board, so that the cover when viewed in plan presents to the eye the combined effect of a circular field and a checker-board included within the outline of said field, within which asphaltum, granolithic, or other matter is introduced and packed therein.

Having thus described my invention, what I claim as new, and desire to secure by Letters Patent, is—

The design for a manhole-cover, substantially as shown and described.

In testimony whereof I have hereunto set my signature in the presence of two subscribing witnesses.

THOMAS P. GREGER.
